UNITED STATES PATENT OFFICE.

MICHAEL F. SILVA, OF HYDE PARK, MASSACHUSETTS.

SPRINKLER SYSTEM.

Application filed May 8, 1926. Serial No. 107,060.

This invention relates to sprinkler heads adapted to be opened at a predetermined heat and has for its object the provision of means whereby a valve to said head may be kept open by a soluble member which is adapted to be dissolved by water discharged from said head and release mechanism which will close the valve, other means being provided for retaining the valve closed until a predetermined heat is reached, when the valve will be released again to permit it to be reopened.

This object is attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as hereinafter shown and described except as required by the scope of the appended claims.

Of the drawings:

Figure 1 represents a side elevation of a sprinkler head embodying the principles of the present invention.

Figure 2 represents a front elevation of same, a portion thereof being shown in section.

Figure 3 represents a vertical section of same on line 3, 3, on Fig. 2.

Figure 4 represents a vertical section of the main valve on line 4, 4 on Fig. 3, and

Figure 5 represents an elevation of the weighted arm.

Similar characters indicate like parts throughout the figures of the drawing.

In the drawings 10 is a water supply pipe having in the line thereof a coupling 11 provided with a branch 12 to which is threaded one end of a valve casing 13 to the opposite end of which is secured a sprinkler head 14 of usual construction.

The valve casing 13 has an oscillating valve plug 15 therein provided with a diametrical passage 16, one end of which is adapted, under normal conditions, to register with the passage 17 in the sprinkler head 14, while the other end, at the same time, will register with the passage 18 in the branch 12 of the pipe coupling 11.

In other words under normal conditions

the valve 15 is open, permitting the water in pipe 10 to freely flow to the sprinkler head 14.

The passage 17 in this head 14 is closed by the member 19 retained in position by the plates 20, 21 connected together by a fusible metal connection 22 which is adapted to melt at a predetermined heat and break the connection between the plates 20, 21 thus permitting the force of the water in the passage 17 to remove the member 19 from its seat.

When this member 19 is displaced the water will be discharged from the passage 17 against the cup-shaped disk 23 which will cause said water to be sprayed in every direction.

It often occurs that a slight fire will be sufficient to fuse the metal connector 22 and cause the water to be discharged through the sprinkler head and thus put out the fire.

Under ordinary conditions, the water will continue to be discharged after the fire is out with the consequence that very much damage will be caused by water and very little by fire.

To prevent this unnecessary damage to property by water is the object of the present invention, and this desired result is accomplished by the following mechanism.

To one end of the oscillating valve plug 15 is secured an arm 24 having a weight 25 at one side of its upper end, this arm being normally in raised position and slightly off center as shown in the drawings.

The arm 24 consists in part of a tube provided with a plurality of perforations 26 and extending upwardly in said tube is a fixed rod 27, the lower end of which is secured to the valve casing 13.

The lower end of the tube 24 has inwardly extending shoulders 28 on which normally rests a soluble locking member 29 formed of metallic calcium or other material which water will dissolve and which retains the arm 24 in its normal raised position.

This locking member 29 is preferably annular and surrounding the fixed rod 27 rests upon the shoulders 28.

These annular members 29 are made of sufficient thickness to maintain the weight of the valve arm 24 and weight 25. It is proposed to construct the members 29 so that an individual unit, when the water strikes it, will dissolve and allow the weight 25 to drop the valve arm after a definite interval of

time and more than one unit may be used if it is desired to increase the interval of time between the fusion of member 22 and the rotation of the valve.

5 Where atmospheric conditions are likely to afford high humidity, it is proposed to coat the calcium units with a layer of glue or cellulose thick enough to keep the calcium dry under normal conditions and thin enough to dissolve almost instantly when wet with a stream of water.

10 The wall of the tube or arm 24 has a slot 30, of a width considerably less than the diameter of the member 29, extending lengthwise of said tube and through which the rod 27 may pass when the tube or arm 24 is unlocked and permitted to move downwardly.

15 The upper end of the tubular arm 24 is curved inwardly toward the disk 23, as at 31, and portions of the water discharged from the head 14 will strike the curved part 31 and will be diverted downwardly onto the soluble locking member 29.

20 When a fire occurs and the heat therefrom fuses the connection 22, thereby permitting the member 19 to be removed from its seat, the water passing through the valve casing 13 will strike the cup-shaped disk 23 and be diverted in every direction.

25 Some of this water thus discharged will pass through the perforations 26 and contact with the locking member 29 causing it to dissolve.

30 As soon as the member 29 has dissolved, the weight 25 will cause the arm 24 to move downwardly, the slot 30 passing over the fixed rod 27 during the initial lowering movement of the arm 24.

35 In the path of the arm 24 is a fusible lug 32 and when the arm 24 has moved downwardly a distance sufficient to move the plug 15 into closed position, said arm will come into contact with this lug 32 which will prevent further downward movement of the said arm.

40 As a consequence, when an incipient fire is started and the metal 22 is fused the sprinkler head will operate to discharge water thereon for a limited period of time, that is, while the locking member is being dissolved, and while the arm 24 is moving downwardly into contact with the lug 32.

45 When the arm 24 has come into contact with the lug 32, the valve 15 will be closed and if water sufficient to extinguish the fire has been discharged, it will remain closed and no more water can be discharged from the sprinkler head, thereby saving considerable property damage from water.

50 If the fire has not been extinguished the increased heat will fuse the lug 32 and release the arm 24 so that it can drop into a vertical position and in so doing again open the valve 15 permitting a continuous flow

of water from the sprinkler until the fire has been extinguished and the water supply to pipe 10 is cut off.

55 It must be understood that the lug 32 is made of material which will only fuse at a greater heat than that which will fuse the metal connection 22.

60 If the fire is so intense at the start that the lug 32 will be fused before the arm 24 starts on its downward movement, said arm will not be retarded in its movement but will move from its highest position to its lowest position without any stop.

65 The lower end of the tubular arm 24 has a cup-shaped portion 33 fitting over the valve stem 34 to which said arm 24 is secured by set screw 35.

70 The valve stem 34 has a squared end 36 which fits into a square opening in the wall 37 of the arm 24.

75 A lug 38 formed on the end of casing 13, by coacting with a projection 39 on the arm 24, limits the upward movement of the arm 24, said projection 39 on the downward movement of arm 24 contacting with the fusible lug 32 and remains in contact therewith until said lug has been fused and removed from the path of said arm.

80 By means of this mechanism a given amount of water may be discharged upon an incipient fire before the supply is cut off and if this is insufficient to extinguish the fire a further and continuous supply of water may be discharged upon said fire.

85 It is believed that the operation and many advantages of the invention will be fully understood without further description.

90 Having thus described my invention, I claim,

95 1. The combination of a supply pipe; a 100 sprinkler head therefor adapted to be opened at a predetermined heat; a valve interposed between said pipe and head and normally open; a weighted arm for moving said valve to close it and by its continued movement again open said valve; soluble means for retaining said arm in raised position, said means being positioned to be acted upon by water discharged from said head whereby to dissolve said means and release said arm and permit it to move downwardly and close the valve; and a member to stop the downward movement of the arm when the valve has been closed, said member being removable from the path of said arm 110 at a heat greater than that necessary to open the head thereby permitting further downward movement of said arm to reopen the valve.

105 2. The combination of a supply pipe; a 115 sprinkler head therefor adapted to be opened at a predetermined heat and discharge water; a valve interposed between said pipe and head and normally open; a weighted arm for moving said valve to close 120

130

it and by its continued movement again open said valve, said arm including a tubular member; soluble means in said tubular member to retain said arm in raised position 5 under normal conditions and positioned to be acted upon by water discharged from said head whereby to dissolve said means and thereby release said arm and permit it to move downwardly and close the valve; and 10 means to stop the arm when the valve has been closed adapted at a predetermined heat greater than that necessary to open the head to be so acted upon as to permit further downward movement of the arm and the re- 15 opening of said valve.

3. The combination of a supply pipe; a sprinkler head therefor having a fusible connection adapted to be released at a predetermined heat to open said head; a valve interposed between said pipe and head and normally open; an arm secured to the stem of said valve and normally off center, said arm having extending lengthwise thereof a perforated tube; an immovable rod extending into said tube and having disposed thereon a locking ring of soluble material positioned to restrain said tube, which ring when dissolved permits said arm to move downwardly and close the valve; and means 25 to stop the downward movement of said arm when said valve has been closed, said stopping means at a heat greater than that necessary to open the head, being adapted to be removed from the path of said arm thereby permitting further downward movement 30 of the arm and the reopening of the valve.

4. The combination of a supply pipe; a sprinkler head therefor having a fusible connection adapted to be released at a predetermined heat to open said head; a valve inter-

posed between said pipe and head and normally open; an arm secured to the stem of said valve and normally off center; said arm having extending lengthwise thereof a perforated tube having a slot extending lengthwise of the wall thereof; an immovable rod extending through said slot and disposed endwise within said tube and having disposed thereon a locking ring of soluble material positioned to restrain said tube, which ring when dissolved permits said arm to move downwardly and close the valve, said rod passing through the slot in said tube during said downward movement; and a fusible member to stop the downward movement of said arm 45 when said valve has been closed, said member when fused permitting further downward movement of the arm and the reopening of the valve. 50

5. The combination of a supply pipe; a sprinkler head therefor having a fusible connection adapted to be released at a predetermined heat to open said head; a valve interposed between said pipe and head and normally open; an arm secured to the stem of said valve and normally off center; soluble means for locking said arm in normal raised position and permitting when dissolved, the downward movement of said arm to close the valve; and means to stop the downward 60 movement of said arm when said valve has been closed, said means, at a heat greater than that necessary to open the head, being adapted to release said arm, thereby permitting further downward movement of the arm 65 and the reopening of the valve. 70
